UNITED STATES PATENT OFFICE.

SIMON W. WARDWELL, OF PROVIDENCE, RHODE ISLAND.

TENSION DEVICE.

No. 849,295.

Specification of Letters Patent.

Patented April 2, 1907.

Application filed May 15, 1905. Serial No. 260,502.

To all whom it may concern:

Be it known that I, SIMON W. WARDWELL, a citizen of the United States, residing in Providence, in the county of Providence and 5 State of Rhode Island, have invented new and useful Improvements in Tension Devices, of which the following is a specification.

My invention relates to tension devices for use with creels, winding-machines, braiding- 10 machines, and for other like purposes.

My invention is particularly adapted for use in multiple where it is required to tension a large number of yarns uniformly, as in a creel with its several hundred supplies.

15 My improvement consists in providing a device which may be used in a series to apply a uniform degree of tension to all of the yarns without particular adjustment of each individual device.

20 My improvement further embraces simplicity of structure and operation, compactness, durability, and the elimination of all liability of derangement of parts.

The accompanying drawings illustrate the 25 preferred form of my invention with several modifications, and its arrangement and operation are fully set forth in the following specification.

Figure 1 is a sectional detail view of the 30 preferred form of my device; Fig. 2, a side elevation of the device in operation; Fig. 3, an end elevation of the same; Figs. 4 and 5, detail views of two different embodiments of the invention.

35 My invention is especially adapted for tensioning yarns delivering over the end from self-supporting cops without the use of spools. The usual method of delivering from creels is from spools supported rotationally to unroll the yarn; but this method is open to many disadvantages which limit the speed at which the yarn can be taken off.

The irregularities in the spools, such as eccentricity of bores and unevenness of the 40 disposition of the weight about the axis, make it impossible to rotate the spools at any considerable speed in unrolling without straining or breaking the yarn. By eliminating the use of spools and employing self- 45 supporting cross-wound packages or cops the yarn may be drawn off over the ends with a speed of delivery which is practically unlimited; but with this system of delivering great difficulty has been experienced in tensioning the yarns to secure the same degree 50

of tension on all of the several hundred ends. With the usual method of adjusting each tension device separately it is practically and commercially impossible to set them all alike. My invention is so simple that it can 60 be operated without particular care or pains on the part of the operator.

In general my device resembles that class of tension in which the yarn runs between two disks or wheels pressed toward each other to apply resistance to the passage of the yarn. The ordinary way of effecting this pressure is by the application of springs, either with two springs, one acting against each disk, or with only one spring acting 70 against one of the disks. In some cases pivoted levers have been employed to act against the disks by means of weights on their free arms. The pressure exerted by springs is always uneven—that is, a spring 75 will bear the hardest on one point of the disk and tend to crimp the latter on its bearing, exerting an uneven pressure on the yarn. It is commercially impracticable to manufacture two or more springs of exactly 80 the same resiliency, so that no two devices could be made to apply the same tension to the yarns. The expedient of an adjustment for each spring has been resorted to; but even with this arrangement it is impossible 85 to adjust the springs of several devices to the same degree of tension. With this method the operator must test each yarn individually by feeling its tension, and it would require a more than ordinary expertise to regulate by human means the tension on a great many yarns. Where levers are used in applying pressure to the disks, the same impracticability of uniformity in manufacture is also experienced. 90 No two levers can be made exactly alike as regards their bearings. An excess of friction at the bearing-point of one lever over that of the other will cause a variation in the force of that lever, and it is impossible in 95 ordinary manufacture to secure absolute uniformity. Therefore the pressure exerted by several levers on their respective disks will not be uniform and the tension on the yarns will vary. 100

105 The improvement of my invention consists in the simple arrangement of elements whereby it is possible to manufacture a great number of the devices all adapted to secure a uniform degree of action without 110

particular care or adjustment on the part of the operator. In other words, with a plurality of the devices of my invention exactly the same degree of tension can be maintained on all of the yarns.

With the device herein described it is not necessary to secure accurate dimensions in manufacture to insure uniform operation of several devices. The pressure applied to the disks is a direct force resulting from the gravity of the weights and without the interposition of levers. If the weights are the same on several of the devices, then the tension applied will be uniform, whereas if, as in other devices, the force were transmitted through levers the tension of several different devices would depend upon the action of the individual levers—that is, if one lever had a free bearing and another a bearing with considerable friction there would be a wide difference in the pressure applied. In manufacturing such a large number of devices as required for the use to which this device is intended it has been found impossible to produce them with the necessary accuracy to secure the uniform tension required.

In the drawings, *a* is a bracket having an inclined face recessed at *b*. Fastened in the bracket and extending from the recess is a stud or pin *c*, preferably of hardened metal. The pin *c* extends at right angles to the face of the bracket, so that it is inclined slightly from the horizontal, the angle of its inclination being preferably about twenty-five degrees, although this may be varied as desired.

Referring particularly to Fig. 1, two disks *d* and *d*² are mounted rotatively and slidably on the pin *c*, and against their outer faces are arranged the resilient washers *e* and *e*², also mounted on the pin *c*. These washers are of felt, fiber, or similar material and may consist of one thickness, Fig. 1, or of several thicknesses, as illustrated in Fig. 4. The inner washer *e* bears against the face of the recess in the bracket *a*, and bearing against the outer washer *e*² is a weight *f*, also slideable on the pin *c* to apply pressure to the disk *d*². The washer *e* is disposed within the recess *b* of the bracket *a*, and on the opposite faces of the weight *f* are similar recesses *g* and *g*², adapted to receive the washer *e*². The purpose of having a recess in each face of the weight *f* is to guard against misplacement of the weight on the pin, which would be liable to occur if the weight were recessed in one face only.

The disks *d* and *d*² are preferably formed with their outer edges rolled over or flanged, and it will be seen that with the washer *e* arranged in the recess *b* and the washer *e*² in the recess *g* the flanges of the disks will extend within said recesses, so that when the yarn is drawn down between the edge of the weight *f* and the bracket *a* it will readily en-

ter between the disks. To further facilitate threading, the bracket *a* is provided with an extension *a*², which in combination with the periphery of the weight *f* forms a guiding-face to guide the thread or yarn between the disks.

The pin *c* extends from the bracket *a* a sufficient distance beyond the weight *f* to accommodate additional weights *h* *h*, &c., which may be added when more tension is required. 75

The bracket *a* may be supported in any suitable manner according to the character of the machine to which the device is attached, a convenient method being that shown in Fig. 2, in which the bracket is formed with a lug *i*, suitably bored to receive a rod *j*, extending from the machine. A set-screw *k* fastens the bracket in position on the rod, the preferable arrangement being to provide a portion of the rod extending beyond the bracket for a guide to the yarn.

The operation of my device is as follows: The yarn is led up from the supply-package *s*, which I have here represented as a cone, and carried across the rod *j*, and thence between the disks *d* and *d*² and partially around the pin *c*, as shown in Figs. 2 and 3. The disks will be separated slightly by the yarn, as shown in Fig. 1, and the pressure of the weights *f* and *h* *h* sliding on the pin *c* against 90 the washer *e*² will apply pressure on the yarn running between the disks. Yarns vary in size and have bunches, slubs, and knots, and when these enlarged portions pass between the disks the latter open slightly to accommodate them. In this way a constant movement or vibration is imparted to the disks, and this movement is taken up by the washers *e* and *e*², which contract each time the disks separate. This feature is of utmost im-

portance, for if the disks were arranged to bear directly on the bracket and weight *f* the latter would have to be moved at each separation of the disks. In moving the weight *f* its inertia would have to be overcome, and this would increase the tension on the yarn at this point. As each bunch or stub passed between the disks the weight would be forced upon the pin *c*, and its momentum would carry it away from the disk *d*², so that all pressure would then be removed from the disk, and consequently no tension would be exerted on the yarn at this point. When the weight slid back against the disk, its momentum would increase the pressure on the yarn, and in this way with the weight *f* constantly sliding up and down and chattering against the disk an irregular or uneven tension would be imparted to the yarn. As now arranged the washers *e* and *e*² provide an elastic yielding element which automatically compensates for any movement of the disks, and in this way a constant even pressure is maintained on the yarn. 120

I have found by experiment that when the 130

yarn is guided or directed to travel in contact with the flat faces of the disk at one side the center or axis thereof the constant vibration of the disks to allow the passage of enlarged places in the yarn sets up a rotary motion of the disks. This although not always essential is a valuable feature, preventing the wearing of grooves in the disks, for as the yarn is drawn between them the rotary movement 5 brings the entire faces of the disks into contact with the yarn, so that whatever wear occurs only goes to smooth and polish the disks evenly. The rotation of the disks also serves to prevent the accumulation of lint or 10 the lodging of nits between the disks.

For most purposes I have found in practice that very little wear will occur on the pin *c* if the latter is properly hardened; but if it is desired to take precautions for greater durability at this point a sleeve or bushing may inclose the pin--as, for instance, in the different ways shown in Figs. 4 and 5. In Fig. 4 a bushing *o* is provided on the pin *c*, having its end bearing against the bracket *a*. The 15 disks and washers are mounted on this bushing, and the latter is free to rotate on the pin, the weight *f* being countersunk at *f*², so as to provide a clearance to prevent the weight bearing on the end of the bushing. The 20 yarn passing over the bushing will rotate the latter, so that the wear is evenly disposed about its periphery. In Fig. 5 the bushing is connected with one of the disks. Thus the disk *d*² is formed with a bushing consisting of 25 the hollow hub or flange *n*, which serves as a bearing on the pin *c*. The other disk *d* is mounted to slide on this flange, and the yarn runs over the flange in passing between the disks. During the rotation of the disks the 30 entire peripheral surface of the flange *n* exposed between the disks is presented to the yarn, so that the wear is evenly distributed over this surface and the device is rendered more durable. Other similar arrangements 35 might be designed for the same purpose.

It will be seen from the foregoing that my device is much more durable than similar devices now known in the art. With the usual form of tension device, in which the yarn 40 passes between two members, the constant friction of the yarn will in time form a groove in one or both of the members. If a coarse 45 yarn is being tensioned, the channel which it forms by wear will be so large that when a finer yarn is used the latter will pass through the groove without any resistance, and therefore the device will not apply any tension to the yarn, and, vice versa, if a fine yarn is used first for any length of time it will wear 50 a narrow groove in the tension members, so that when a coarser yarn is applied the latter will not sink into the groove, but will rub on the edges, creating excessive friction and abrading and injuring the surface of the yarn.

65. Besides being practically indestructible

and so simple as to be proof against derangement or getting out of order my device is also most compact. For these reasons its use is particularly advantageous on creels where there are from four hundred to six hundred 70 yarns to be tensioned. After the proper number of weights are applied to secure the required degree of tension in one device the operator has only to apply an equal number of weights to all of the other devices, and the 75 same degree of tension for all of the yarns is then assured. It will be seen that the operator is relieved of all the responsibility of adjustment or care always necessary where spring tensions with adjustable devices for 80 varying pressure or similar devices are employed

I am aware that various arrangements of disk or wheel tensions have heretofore been used in the art. Therefore I do not claim the 85 invention of wheel tensions broadly, but only the particular novel arrangement herein described, whereby I attain the advantages specified.

What I claim is—

1. In a tension device, the combination 90 with a bracket having an inclined face, a pin projecting perpendicular to said face, resilient washers surrounding the pin and one of them bearing on the face, two disks mounted 95 on the pin between the washers, and a weight slidable on the pin to engage the other washer to apply pressure to the disks.

2. In a tension device, the combination 100 with a bearing-pin, of two adjacent disks mounted on the pin, resilient washers engaging the outer faces of the disks, and means to exert pressure on the washers to force the disks together, including a weight slidable on the pin through gravity, to engage one of the 105 washers.

3. The combination in a tension device 110 with a stud or pin, of wheels or disks mounted rotatively on the pin and a weight sliding on the pin through gravity, to press the disks together.

4. The combination in a tension device 115 with a stud or pin, of resilient washers on the pin, disks rotatable upon the pin between the washers, and a weight slidable on the pin through gravity, to apply pressure on the washers.

5. The combination in a tension device 120 having rotatable disks with coinciding flat faces, of means for directing a thread to travel between the disks in a curve in contact with the faces thereof to rotate the same, and a weight directly engaging one of the disks to press the same toward the other by gravity.

6. The combination in a tension device 125 adapted to apply tension to a running thread, of an inclined pin over which the thread runs, disks mounted on the pin and rotated by the action of the thread, resilient washers engaging the outer faces of the disks, 130

and a weight mounted on the pin to slide through gravity to apply pressure through the washers to the disks.

7. The combination in a tension device adapted to act on a running thread, of a pin supported at an angle to the horizontal, a rotative bushing on the pin over which the thread runs, two disks rotatable in respect to the pin, resilient washers engaging the outer faces of the disks, and a weight sliding on the pin, through gravity, to engage one of the washers.

8. The combination in a tension device adapted to act on a running thread, of an inclined stud or pin, a disk, formed with a hub or flange over which the thread runs, mounted rotatively on the pin, a second disk mounted rotatively on the hub, resilient washers engaging the outer faces of the disks, and a weight slideable on the pin to engage one of the washers through gravity.

9. The combination in a tension device with a bracket, having an inclined recessed face, a stud or pin projecting from said face, a slideable weight on the stud, with its faces

recessed to correspond with the bracket, resilient washers arranged in the recesses, and two disks mounted rotatively on the pin between the washers, and having their edges flanged outward to project within the recesses of the bracket and weight, substantially as shown and described.

10. The combination in a tension device having rotatable disks with coinciding flat faces, of means for directing a thread to travel between the disks in a curve in contact with the faces thereof to rotate the same, a weight directly engaging one of the disks to press the same toward the other by gravity, and an elastic backing of a character to permit the separation of the disks under the action of the thread without changing the position of the pressure means.

In testimony whereof I have signed my name to this specification in the presence of two subscribing witnesses.
